UNITED STATES PATENT OFFICE.

JOHN C. BARBER, OF CHICAGO, ILLINOIS, ASSIGNOR TO STANDARD CAR TRUCK COMPANY, OF CHICAGO, ILLINOIS, A CORPORATION OF NEW JERSEY.

CAR-TRUCK.

1,316,553.

Specification of Letters Patent. Patented Sept. 23, 1919.

Application filed January 31, 1919. Serial No. 274,189.

To all whom it may concern:

Be it known that I, JOHN C. BARBER, a citizen of the United States, residing at Chicago, in the county of Cook and State of Illinois, have invented certain new and useful Improvements in Car-Trucks; and I do hereby declare the following to be a full, clear, and exact description of the invention, such as will enable others skilled in the art 10 to which it appertains to make and use the same.

My invention has for its object to provide certain improvements in freight car trucks, with a view of better adapting the same to 15 present conditions and demands of the railway service; and, to this end, my invention consists of the novel devices and combinations of devices hereinafter described and defined in the claims.

20 My invention is illustrated in the accompanying drawings, wherein like notations refer to like parts throughout the several views.

In said drawings,

25 Figure 1 is a view in side elevation, partially in diagram, showing one of the side frames and some of the associated parts of the car truck;

Fig. 2 is a detail in perspective, showing 30 one end portion of the spring plank detached and turned up-side down;

Fig. 3 is a view of the central portions of the truck in cross section, with some portions shown in elevation, the sections of the 35 opposite ends being in different vertical planes, the parts being shown as they appear when the lateral motion rollers are in working position;

Fig. 4 is a view similar to Fig. 3, but with 40 the parts shown as they appear after the lateral motion rollers have been removed and the interlocked bolster and spring plank have become interlocked to the side frames;

Fig. 5 is a sectional view corresponding 45 to that shown at the left end of Fig. 3, but showing the parts on a much larger scale; and

Fig. 6 is a sectional view corresponding to that shown at the left end of Fig. 4, but 50 showing the parts on a much larger scale, the scale being the same as in Fig. 5.

The steel side frames 7, shown in the drawings, are of a well known standard type and are provided with the customary centrally located bolster spaces 8, the vertical

walls of which serve as bolster columns 9, and which spaces 8 are laterally enlarged below the vertical travel line of the bolster, in order to permit the endwise insertion and removal of the bolster 10 in the usual way. 60 The bolster 10 is of the form standardized by the Government, so far as its general shape and its main features are concerned. Said bolster is also spring-supported from the opposite ends of the spring plank 11 65 through the springs 12, applied in the customary way. The said spring plank 11 is, however, made of a special form and the bolster 10 is slightly modified for the incorporation of my improvements into this 70 otherwise standard truck.

The spring plank 11 is a steel casting, preferably of channel form, and is provided with a central pin 13 cast integral therewith adapted to project upward through a central seating hub 14 therefor, formed in the bolster co-incident with the central part of the bolster center plate 15, and which is made long enough to project therethrough and serve also to connect the center plate 75 of the body bolster (not shown) with the center plate of the truck bolster. The presence of this pin 13, so related to the bolster 10, serves to interlock the said bolster and spring plank against any lateral movement 80 of one in respect to the other, while permitting freedom of vertical motion of the bolster relative to the spring plank.

The spring plank 11 is also provided, on its under side, with bearing surfaces 16, for 90 co-operation with lateral motion rollers 17 resting on corresponding seats 18, formed in the side frames, at the bottoms of the bolster spaces. The rollers 17 are cylindrical and the seats 16 and 18 for the same in the 95 spring plank and the side frames have contours, of the well known Barber type, disclosed and claimed in Lee W. Barber Patent, 784,096, of March 7, 1905.

It must be obvious that with the said 100 bolster 10 and spring plank 11 related and bolster and spring plank 11 related and interlocked together, as above described, and the rollers 17 present, as shown in Figs. 1, 3 and 5, the said bolster and spring plank 105 will be free to travel together laterally with the said side frames, or crosswise of the truck on the said rollers 17 moving in the said bearings 16 and 18, when the car is traveling around curves, and that, because 110

of the contours of these roller-bearing seats, the bolster and spring plank and the car body, when in position, will return to their normal or central positions with the rollers 5 at the lowest points of said seats, automatically, after the truck and the car again get onto the straight sections of the track. This lateral motion, of course, must be limited and, for this purpose, the spring plank 11 10 is shown with deep lugs 19 depending from its lower side, adapted to abut the inner edges of those portions of the side frames at the bottom of the bolster spaces, and the bolster 10 is provided on the side walls of 15 its outwardly projecting ends with lugs 20, adapted to abut against the outer faces of the side frames adjacent to the bolster spaces to limit the lateral movement of the bolster. The lugs 19 on the spring plank 20 25 11 and the lugs 20 on the bolster coöperate to limit this lateral travel of the interlocked bolster and spring plank; and hence, they should be correspondingly spaced relative to the walls of the side frames, so they will 25 strike the said side frames at the same time.

The said spring plank 11 is also provided with two additional sets of downwardly depending lugs, marked, respectively, 30 21 and 22. The lugs 21 depend from the very outer ends of the spring plank 11, whereas, the lugs 22 depend from the spring plank inward of its roller-bearing seats 16 and outward of the lateral motion stop lugs 19. The relations of these three sets of lugs 19, 35 21 and 22 are best shown in Fig. 2 of the drawing.

The said pair of lugs 21 and 22, depending from the spring plank 11, are so related to each other and these portions of the 40 side frames directly below the spring plank that, when the rollers are removed, the said lugs 21 and 22 will respectively engage with the opposite vertical walls of the underlying portions of said side frames, as shown in 45 Figs. 4 and 6 of the drawings, and thereby cause the interlocked bolster and spring plank to become interlocked with the side frames of the truck, and thereafter confine the bolster to a vertical motion only. In 50 other words, when this simple change is made, a truck is afforded wherein no lateral motion is permitted to the truck bolster or car body carried thereby.

If the removal of the rollers 17 permits 55 the truck bolster 10 and spring plank 11 to drop too far to maintain the desired standard level of the drawbar on the car body, shims 23 can be inserted under the bolster and above the spring caps 24, as shown in 60 Figs. 4 and 6, so as to maintain said required standardized level of the truck bolster and car body. The division walls between the roller-bearing seats 16 of the spring plank 11 and the roller-bearing seats 18 formed 65 on the side frames might, however, be made

deeper, so as to meet sooner and reduce the drop, when the rollers are removed, to such an extent that the change in the drawbar level would be negligible, and, in such case, it would not be necessary to employ the 70 shims 23 between the spring caps and rollers.

The bolster is preferably recessed at the proper points on its under surface to seat and hold the spring caps 24, when the rollers are 75 present, as shown in Figs. 3 and 5, or to take the shims when the rollers are removed, as shown in Figs. 4 and 6. The spring caps 24 are shown as provided with depending dowels 25 for centering the upper ends of 80 the springs 12. The spring plank 11 has countersunk seats 26 for the springs 12 on its upper surface, and these seats 26 are provided with upwardly projecting dowels 27 for centering the lower ends of said springs 85 12. The springs are thus securely held against any lateral displacement in respect to the bolster or the spring plank.

The opposite walls of the bolster spaces 8 of the side frames, below the lateral enlargement of said bolster spaces, are provided with lugs 28, adapted to receive between them the spring plank 11 and guide the same in its lateral travel, and hold the same from forward and backward displacement, both when mounted for lateral motion and when interlocked with the side frames. 95

From the foregoing, it will be seen that, by my improvement, I provide a freight car truck of simple structure and low cost, 100 which is normally adapted to afford lateral motion of the spring plank and bolster on anti-friction devices, and hence, also of the car body carried by the truck bolster; but wherein the said spring plank and bolster 105 can be instantly interlocked with the side frames, upon the removal of the anti-friction rollers, thereby confining the bolster to a vertical motion only, as in the standard Government truck. The diversity in demand, found among different railway organizations, due to divergence in views 110 among different controlling railway engineers, thus is met by a single truck.

What I claim is:—

1. A car truck having a spring-mounted bolster and supporting devices therefor provided with means interchangeably adapted for coöperation with lateral motion anti-friction devices, to permit both vertical and lateral motion of said bolster on the side frames of the truck, or to be interlocked with said side frames, when said anti-friction devices are removed, so as to confine said bolster to vertical motion only, substantially as 125 described.

2. A car truck having a spring-mounted bolster and a spring plank interlocked against any lateral motion of either the plank or the bolster in respect to each other 130

but permitting vertical motion of the bolster in respect to the plank, the said spring plank and bolster together being capable of lateral motion, substantially as described.

5 3. A car truck having a spring-mounted bolster and a spring plank interlocked to the bolster with freedom for vertical motion of the bolster relative to the plank and which spring plank is provided with means interchangeably adapted for coöperation with lateral motion anti-friction devices, or to be interlocked with the side frames when said anti-friction devices are removed, substantially as described.

10 4. A car truck having a spring-mounted bolster and a spring plank interlocked together against any lateral motion of the bolster or the plank in relation to each other but with freedom for vertical motion of the bolster in respect to the plank and which plank is provided on its under surface with roller-bearing seats adapted to coöperate with roller bearings seated on said frames, to afford lateral motion of said interlocked bolster and spring plank, and also provided with depending lugs adapted to interlock with the side frames of the truck when said roller bearings are removed, thereby confining the bolster to vertical motion only, substantially as described.

15 5. In a car truck, the combination with

side frames having lateral motion roller-bearing seats between the bolster columns and lateral motion rollers thereon, of a bolster and spring plank interlocked together 35 against lateral motion of either in respect to the other and which spring plank is provided on its under side with roller-bearing seats for coöperation with said rollers, whereby the spring plank and bolster are 40 supported from the side frames with freedom for lateral motion thereon, substantially as described.

6. In a car truck, the combination with the side frames provided with anti-friction 45 lateral motion devices located in the bolster spaces at the bottoms thereof, of a spring plank having bearing surfaces resting on said anti-friction devices, a bolster spring-supported from the said plank, and a center 50 pin fixed to the spring plank and extending upward through the center of the bolster and serving to interlock said bolster and plank together for common lateral movement while permitting vertical motion of 55 the bolster, substantially as described.

In testimony whereof I affix my signature in presence of two witnesses.

JOHN C. BARBER.
